QUATERNARY SALTS

Theodore I. Fand, White Plains, N. Y., assignor to Nepera Chemical Co., Inc., Nepera Park, Yonkers, N. Y., a corporation of New York

No Drawing. Application June 9, 1954,
Serial No. 435,617

16 Claims. (Cl. 260—256.4)

This invention relates to quaternary compounds and relates more particularly to certain quaternary salts of thonzylamine, i. e., N,N-dimethyl-N'-(p-methoxybenzyl)-N'-(2-pyrimidyl)-ethylene diamine.

An object of this invention is the production of novel quaternary ammonium salts having desirable solubilizing and other surfactant properties.

Another object of this invention is the provision of novel solubilizing agents which are particularly valuable as solubilizing agents for antibiotics such as, for example, gramicidin, tyrothricin, subtilin, etc.

A further object of this invention is the provision of quaternary ammonium salts which are effective mucolytic agents for the solubilization of secretions of the nose, throat and lungs, and which may be administered satisfactorily by aerosolization techniques.

Other objects of this invention will appear from the following detailed description.

The solubilization of many therapeutic organic compounds frequently presents a serious problem in the practical application of such compounds, especially where the use of organic solvents, such as alcohol, is undesirable. Thus, for example, gramicidin is quite insoluble in water, and where the use of an aqueous medium is of importance, the only manner in which the gramicidin can be employed is in the form of a suspension. Not only does this limit the practical concentration of the antibiotic which can be made available for action, but the preparation of stable suspensions is also a matter of no little difficulty.

I have now found that quaternary ammonium salts of the general formula

where R is an alkyl group up to about 20 carbon atoms and X is the anion of an acid, comprise highly effective solubilizing agents which are particularly valuable for solubilizing difficultly soluble antibiotics. In addition, these salts exhibit bacteriostatic action against various organisms, especially *Staphylococcus aureus* and as such, comprise highly effective disinfectant materials.

The novel quaternary ammonium salts of my invention are also highly effective as mucolytic agents and exhibit marked ability to reduce the viscosity of many thick, tenacious secretions of the nasal, pharyngeal and bronchial passages frequently encountered in cases of pneumonia and pulmonary tuberculosis. One highly effective manner of administering these quaternary ammonium salts for maximum mucolytic activity is in the form of an aerosol. This technique involves the nebulization of a predetermined amount of an aqueous solution containing from as little as 0.01% to 1.0% by weight of the quaternary ammonium salt into a relatively confined space, such as a tent or, preferably, a mask, and the patient under treatment in-

2

hales the resulting mist or aerosol. The mucolytic agent is thus brought into direct and intimate contact with the secretions present in the nose, throat and lungs. This therapy causes a marked loosening and liquefaction of the secretions. In many instances the sputum flow is greatly increased. The application of the novel quaternary ammonium salts of my invention to the treatment of the premature new-born by this aerosolization technique is particularly effective in those instances where the infants are born with or develop atelectasis. The nebulization of an aqueous solution of said quaternary ammonium salt into an isolette, incubator or croup tent to produce an aerosol has been associated with a definite decrease in mortality of such premature infants. The aerosol may also be administered concurrently with oxygen therapy.

A typical formulation which has been found to be clinically effective in mucolytic therapy contains 0.15 to 0.20 gram of N,N-dimethyl-N'-(p-methoxybenzyl)-N'-(2-pyrimidyl)-N-cetyl-N-bromo-éthylène diamine, or other 20 of the novel quaternary ammonium salts of my invention, dissolved in 10.0 grams of propylene glycol, which is then brought up to a volume of 100 ml. with distilled water and buffered to a pH of 7.4 with sodium carbonate.

As examples of acid anions which may constitute that 25 portion of the above general formula represented by the substituent X, there may be mentioned the anions of such inorganic acids as hydrochloric acid, hydrobromic acid, hydroiodic acid, sulfuric acid and the several phosphoric acids. Those compounds containing halogen as the inorganic anion in the quaternary ammonium salt structure are preferable since they are most conveniently and economically obtained.

The novel salts of my invention may be produced, for example, by dissolving the thonzylamine base in a suitable organic solvent such as benzol, toluene or xylene, and then adding an alkyl halide to the solution. Upon standing or upon moderate heating, the desired alkyl halide quaternary ammonium salt of thonzylamine is formed. The amine base may also be reacted with an alkyl halide directly and without the use of a solvent by mixing the reactants and warming at 40° to 100° C., for about 8 to 72 hours. Mol ratios are preferably employed. The iodide, bromide or chloride may be readily formed in this manner. If an iodide salt is formed initially, it may be readily converted to the corresponding bromide or chloride salt by reacting said iodide salt with either silver bromide or with silver chloride, for example, so as to replace the iodine in the salt by an atom of chlorine or bromine as the case may be. Furthermore, the bromide, chloride or iodide salt may also be converted to the corresponding sulfate salt by reacting these halogen salts with silver sulfate or, where a phosphate salt is desired, by reacting any one of the halide salts with silver phosphate.

In addition, the novel quaternary salts of my invention may also be made by reacting an N-(p-methoxybenzyl)-N-(2-pyrimidyl)-ethyl halide with a dimethyl alkyl amine. As brought out above, where the halogen atom present is iodine, the quaternary iodide obtained may be converted to the chloride or bromide or any other anion may be substituted.

In order further to illustrate my invention, but without being limited thereto, the following examples are given:

65

Example 1

2.86 parts by weight of thonzylamine base are dissolved in 22 parts by weight of benzol and to the solution thus obtained are added 1.42 parts by weight of methyl iodide. The reaction mixture is maintained at room temperature and the quaternary ammonium salt N,N-dimethyl-N'-(p-methoxybenzyl)-N'-(2-pyrimidyl)-ethylene diamine-

3

N-methyliodide precipitates from the solution. This novel compound has a melting point of 168-169° C.

Example II

2.86 parts by weight of thonzylamine base and 1.8 parts by weight of N-amyl bromide are mixed in a suitable vessel and the reaction mixture obtained then heated at a temperature of 100° C. for 48 hours. The mixture is then cooled and the residue recrystallized from a mixture of ethyl ether and isopropanol in a ratio of 3:2 parts by weight to yield 10 white crystals. The N,N-dimethyl-N'- (p-methoxybenzyl)-N'- (2-pyrimidyl)-ethylene diamine-N-amyl bromide thus obtained melts at a temperature of 127-128.5° C. and is soluble in water and alcohols, such as methyl, ethyl and isopropyl alcohol.

Example III

2.86 parts by weight of thonzylamine base and 2.5 parts by weight of N-decyl bromide are heated together at about 100° C. for 48 hours, the reaction mixture cooled to about 20° C. and then extracted with ether by decantation. On being allowed to stand, the ether-insoluble residue solidifies and upon recrystallization from a 3:2 mixture of ether-isopropanol by weight, white crystals of N,N-dimethyl-N'- (p-methoxybenzyl)-N'- (2-pyrimidyl)-ethylene diamine-N-decyl bromide are obtained. This compound has a melting point of 105-107° C. This novel quaternary ammonium salt is soluble in water and in the alcohols mentioned in Example II.

Example IV

2.86 parts by weight of thonzylamine base and 5 parts by weight of lauryl bromide are heated together at about 100° C. for 48 hours, the reaction mixture cooled to about 20° C. and then extracted with ether by decantation. On being allowed to stand, the ether-insoluble residue solidifies. Upon recrystallization of the ether-insoluble residue from a mixture of ether-isopropanol in a ratio of 3:2 parts by weight, a yield of 5 parts by weight of N,N-dimethyl-N'- (p-methoxybenzyl)-N'- (2-pyrimidyl)-ethylene diamine-N-lauryl bromide is obtained in the form of white crystals. The product obtained has a melting point of 107.5-108° C., is soluble in ethyl alcohol, and slightly soluble in water.

Example V

By reacting 2.86 parts by weight of thonzylamine base and 10 parts by weight of n-decyl iodide in the manner described in Example III, 8.5 parts by weight of N,N-dimethyl-N'- (p-methoxybenzyl)-N'- (2-pyrimidyl)-ethylene diamine-N-decyl iodide are obtained in the form of light yellow crystals having a melting point of 96-97° C. This compound is slightly soluble in water and soluble in ethyl alcohol.

Example VI

By reacting 2.86 parts by weight of thonzylamine base and 10 parts by weight of cetyl iodide in the manner described in Example III, 8.3 parts by weight of N,N-dimethyl-N'- (p-methoxybenzyl)-N'- (2-pyrimidyl)-ethylene diamine-N-acetyl iodide are obtained in the form of light yellow crystals which have a melting point of 92-94° C. This compound is soluble in ethyl alcohol.

Example VII

By reacting 2.86 parts by weight of thonzylamine base and 10 parts by weight of dodecyl iodide in the manner described in Example III, 8.0 parts by weight of N,N-dimethyl-N'- (p-methoxybenzyl)-N'- (2-pyrimidyl)-ethylene diamine-N-dodecyl iodide are obtained in the form of light yellow crystals having a melting point of 96-98° C. This compound is soluble in ethyl alcohol.

Example VIII

5.8 parts by weight of thonzylamine base are reacted

4

with 10 parts by weight of cetyl bromide at about 100° C. for 48 hours and after being cooled at 20° C. the reaction mixture is extracted with ether. On cooling the raffinate, solidification takes place and the recrystallization of the solid material from ether-isopropanol yields 5.5 parts by weight of white crystalline N,N-dimethyl-N'- (p-methoxybenzyl)-N'- (2-pyrimidyl)-ethylene diamine-N-acetyl bromide. This compound has a melting point of 91-92° C., is soluble in alcohol and is slightly soluble in water.

Example IX

1.18 parts by weight of the cetyl bromide quaternary ammonium salt of thonzylamine prepared as described in Example VIII are dissolved in 75 parts by weight of water 15 warmed to 80° C. and a solution of 0.312 part by weight of silver sulfate in 100 parts by weight of water at 80° C. is added thereto. The resulting mixture is warmed at about 100° C. until the precipitate of silver bromide which forms has coagulated. The silver bromide is filtered off 20 and the filtrate evaporated. The N,N-dimethyl-N'- (p-methoxybenzyl)-N'- (2-pyrimidyl)-ethylene diamine-N-cetyl sulfate obtained is a yellow oil.

Example X

1.1 parts by weight of the n-decyl iodide quaternary ammonium salt of thonzylamine prepared as described in Example V are dissolved in 50 parts by weight of ethanol and to this solution is added a solution of 0.34 part by weight of silver nitrate in 50 parts by weight of ethanol. 25 The precipitate of silver iodide which forms is filtered off. The filtrate is evaporated to dryness and then recrystallized from ether-isopropanol to yield a white crystalline product. The N,N-dimethyl-N'- (p-methoxybenzyl)-N'- (2-pyrimidyl)-ethylene diamine-N-decyl nitrate obtained 30 melts at 101-102° C. and is soluble in alcohol and slightly soluble in water.

Example XI

1.16 parts by weight of the n-dodecyl iodide quaternary ammonium salt of thonzylamine obtained in accordance 40 with the process of Example VII are stirred in 1000 parts by weight of water at 80° C. and 1.14 parts by weight of silver chloride are then added. The mixture is then heated to about 100° C. and maintained at this temperature for about 48 hours with stirring. The precipitate of silver iodide formed is filtered off and, after the filtrate is evaporated to dryness, the residue is recrystallized from ether-isopropanol to yield white crystals. The N,N-dimethyl-N'- (p-methoxybenzyl)-N'- (2-pyrimidyl)-ethylene diamine-N-n-dodecyl chloride obtained has a 50 melting point of 75-78° C. and is soluble in water and alcohol.

The novel quaternary ammonium salts of thonzylamine of my invention are as stated, effective disinfecting agents against various bacteria. In vitro tests against *Staph. aureus* demonstrate that the n-decyl bromide, lauryl bromide, cetyl bromide and n-decyl iodide quaternary salts of thonzylamine, for example, show effective bacteriostasis in concentrations of less than 0.25 mg.%.

60 The test is carried out as follows:

10 ml. of a suitable nutrient medium is added to each of ten test tubes and the compound to be tested is dissolved or suspended in some of the nutrient medium in a concentration of 128 mg.%. 10 ml. of the resulting 65 solution is added to the second tube and the mixture thoroughly mixed. 10 ml. of the mixture is removed from the second tube, added to the third tube, mixed and the dilution method continued down through the tenth tube. The 10 ml. removed from the last tube are discarded. 70 The first tube, to which nothing is added, serves as a control. The concentration of the test compound in the tubes varies in amount from 64 mg.% down to 0.25 mg.%. Each tube is then inoculated with an inoculum of 0.1 ml. of a 1-500 dilution of an 18 hour culture of *Staph. aureus*, 75 and the tubes incubated for 72 hours. The bacteriostatic

end-point is taken as the lowest concentration of the test compound in which no growth can be observed.

Utilizing this technique, the cetyl bromide quaternary salt of thonzylamine is effective as a bacteriostat against *Vibrio metchnikovii* in a concentration of 0.2 mg.%, against *Streptococcus faecalis* in a concentration of 0.16 mg.%, against *Clostridium welchii* in a concentration of less than 0.04 mg.% and against *Bacillus subtilis* in a concentration of less than 0.04 mg.%. This compound is also quite active against *Streptococcus hemolyticus* and *Klebsiella pneumoniae*.

In addition to the antibacterial activity exhibited by the quaternary ammonium salts of thonzylamine, these compounds also exhibit marked antifungal activity and are particularly active against *Trichophyton mentagrophytes*, *Trichophyton rubrum*, *Sporotrichum schenckii* and *Penicillium digitatum*. For example, against *Trichophyton mentagrophytes* the cetyl bromide quaternary of thonzylamine is fungistatic in a concentration of 0.2 mg.%, against *Trichophyton rubrum* in a concentration of 0.04 mg.%, against *Sporotrichum schenckii* in a concentration of 0.2 mg.% and *Penicillium digitatum* in a concentration of 1 mg.%. This compound is also fungistatic in a concentration of 5 mg.% against *Candida albicans*.

A particularly valuable property of my novel quaternary ammonium salts of thonzylamine is their ability to disperse or solubilize antibacterial agents, such as gramicidin. I have been able to prepare a clear aqueous dispersion containing 1% by weight of thonzylamine hydrochloride, 0.25% by weight of 1-phenylephrine hydrochloride, 0.005% by weight of gramicidin, 2% by weight of a mixture of monobasic sodium phosphate and dibasic sodium phosphate and .001% by weight of "Paraben" preservative (mixed methyl and propyl esters of p-hydroxybenzoic acid) with the aid of 0.1% by weight of my novel thonzylamine quaternary ammonium salts such as, for example, the cetyl bromide or lauryl bromide quaternary ammonium salt. The solution remains clear and stable.

This application is a continuation-in-part of my pending application S. No. 276,671, filed on March 14, 1952, and now abandoned.

It is to be understood that the foregoing detailed description is given merely by way of illustration and that many variations may be made therein without departing from the spirit of my invention.

Having described by invention, what I desire to secure by Letters Patent is:

What I claim is:

1. Quaternary ammonium salts of the formula

where R is an alkyl group and X is an anion of the group having up to 20 carbon atoms consisting of sulfate, phosphate, nitrate chloride, bromide and iodide.

2. N,N - dimethyl-N'-(p-methoxybenzyl)-N'-(2-pyrimidyl)-ethylene diamine-N-cetyl bromide.

3. N,N - dimethyl-N'-(p-methoxybenzyl)-N'-(2-pyrimidyl)-ethylene diamine-N-lauryl bromide.

4. N,N - dimethyl-N'-(p-methoxybenzyl)-N'-(2-pyrimidyl)-ethylene diamine-N-n-decyl iodide.

5. N,N - dimethyl-N'-(p-methoxybenzyl)-N'-(2-pyrimidyl)-ethylene diamine-N-n-decyl bromide.

6. N,N - dimethyl-N'-(p-methoxybenzyl)-N'-(2-pyrimidyl)-ethylene diamine-N-n-dodecyl chloride.

7. Process for the production of quaternary ammonium salts of N,N-dimethyl-N'-(p-methoxybenzyl)-N'-(2-pyrimidyl)-ethylene diamine which comprises reacting

said amine compound with an alkyl halide in which the halogen is a member of the group consisting of chlorine, bromine and iodine wherein said alkyl group has up to 20 carbon atoms.

5. Process for the production of quaternary ammonium salts of N,N-dimethyl-N'-(p-methoxybenzyl)-N'-(2-pyrimidyl)-ethylene diamine which comprises reacting said amine compound with an alkyl halide in which the halogen is a member of the group consisting of chlorine, bromine and iodine and said alkyl group contains up to 20 carbon atoms, and then replacing said halogen atom with the anion of another acid by reacting the quaternary ammonium alkyl halide thus obtained with the silver salt of said acid.

9. Process for the production of N,N-dimethyl-N'-(p-methoxybenzyl) - N' - (2-pyrimidyl)-ethylene diamine-N-cetyl sulfate which comprises reacting N,N-dimethyl-N'-(p-methoxybenzyl) - N'-(2-pyrimidyl)-ethylene diamine-N-cetyl bromide with silver sulfate.

10. Process for the production of N,N-dimethyl-N'-(p-methoxybenzyl) - N' - (2-pyrimidyl)-ethylene diamine-N-decyl nitrate, which comprises reacting N,N-dimethyl-N'-(p-methoxybenzyl) - N'-(2-pyrimidyl)-ethylene diamine-N-decyl iodide with silver nitrate.

11. Process for the production of N,N-dimethyl-N'-(p-methoxybenzyl)-N'-(2-pyrimidyl)-ethylene diamine-N-n-dodecyl chloride which comprises reacting N,N-dimethyl-N'-(p-methoxybenzyl)-N'-(2-pyrimidyl)-ethylene diamine-N-dodecyl iodide with silver chloride.

12. Process for the production of quaternary ammonium salts of N,N-dimethyl-N'-(p-methoxybenzyl)-N'-(2-pyrimidyl)ethylene diamine which comprises reacting said amine compound with an alkyl halide in which the halogen is a member of the group consisting of chlorine, bromine and iodine and said alkyl group contains up to 20 carbon atoms, said reaction being carried out at a temperature of 40 to 100° C. for 8 to 72 hours.

13. Process for the production of N,N-dimethyl-N'-(p-methoxybenzyl) - N'-(2-pyrimidyl)-ethylene diamine-N-cetyl bromide which comprises reacting N,N-dimethyl-N'-(p-methoxybenzyl)-N'-(2-pyrimidyl)-ethylene diamine with cetyl bromide.

14. A mucolytic agent comprising an aqueous solution of a quaternary ammonium salt of the formula

55 where R is an alkyl group having up to 20 carbon atoms and X is an anion of the group consisting of sulfate, phosphate, nitrate, chloride, bromide and iodide.

15. A mucolytic agent in accordance with claim 14 and containing from 0.01 to 1.0% by weight of said quaternary ammonium salt.

16. A mucolytic agent in accordance with claim 14 containing propylene glycol and from 0.01 to 1.0% by weight of said quaternary ammonium salt.
